UNITED STATES PATENT OFFICE.

JAMES LUTHER HOSACK, OF WOODSTOCK, ONTARIO, CANADA, ASSIGNOR TO STANDARD TUBE & FENCE CO., LTD., OF WOODSTOCK, ONTARIO, CANADA.

MACHINE FOR FORMING TUBES.

1,266,470.

Specification of Letters Patent.

Patented May 14, 1918.

Application filed September 10, 1917. Serial No. 190,526.

To all whom it may concern:

Be it known that I, JAMES LUTHER HOSACK, a subject of the King of Great Britain, residing in the city of Woodstock, in the 5 Province of Ontario, Dominion of Canada, have invented certain new and useful Improvements in Machines for Forming Tubes, of which the following is a specification.

This invention relates to improvements in 10 machines for forming tubes of the type in which tubes are formed from strips of metal passed longitudinally through a plurality of forming rolls and dies, to give them their final shape and the objects of the invention 15 are to enable the forming operation to be more effectually performed.

According to the present invention, a forming roll having a stationary axis is provided adapted to coöperate with a series 20 of flat dies in endless chain formation adapted to move axially with the tube over a plane surface opposite the roll in the manner hereinafter explained and more fully set forth in the accompanying specification 25 and drawings.

Referring to the drawings:

Figure 1 is a side view of the portion of the machine embodying the present invention.

30 Fig. 2 is a longitudinal sectional view therethrough.

Fig. 3 is a perspective view of one of the flat forming dies.

35 Fig. 4 is a plan view of one of the flat forming dies.

Fig. 5 is a cross sectional view of one of the flat forming dies.

40 Fig. 6 is a transverse section through one of the forming rolls and dies.

45 In the drawings like characters of reference indicate corresponding parts in each figure.

The present invention is designed to form part of a tube forming machine, and the 45 function performed by the coöperating rolls and dies, which depends upon the shape of the die surface, is usually that of effecting the final closing of the tube.

50 Referring to the drawings, A represents the frame of the machine which supports a plurality of pairs of rolls B, single rolls 10 and guides 11. The nature and construction and number of the forming rolls and dies does not form part of the present invention, and is disclosed in the United States

Patent No. 724426. Certain of these rolls will be driven by gearing in the usual way to draw or force the metal which is to be formed through the machine.

The present invention includes a forming 60 roll C having a stationary axis and an endless series of flat forming dies D. The stationary roll is supported from suitable adjustable bearing blocks 12 of any desired character. The roll C may be power driven 65 if desired, or may simply be permitted to be turned by the frictional contact of the tube as it is drawn through the machine.

The endless series of forming dies D comprise carriers 13 and die blocks 14 70 mounted on the carriers. Each carrier is formed on opposite ends with lugs 15 adapted to enter between lugs 16 and 17 on the adjacent blocks, the said lugs being adapted to receive a suitable pivot pin 18, 75 whereby the carriers form an endless chain. The die block 14 itself may be made of steel heat treated for proper hardness and suitably grooved for the size of the tube. It is fastened to and held in alignment with 80 the carrier by a tongue 19 fitting in a groove 20 in the carrier, being held therein by suitable means, such as dowel pins 21 and fillister headed cap screws 22.

The endless series of carriers 13 are 85 guided in position opposite the forming roll C by means of a semi-circular guide-way E, having side flanges 23 and 24 held in position by the screws 25 and 26. The guide way itself is adjustably held in position, 90 the means I have shown to accomplish this comprising clamping bolts 27 extending through the frame and through slots 28 in a flange or web 29 on the guide way.

The guide-way E is formed opposite the 95 roll C with a flat or plane face 30^a, the length of which is equal to or greater than the length of two of the dies, whereby two of the dies will always be in position opposite the forming roll with their faces in 100 alignment, and parallel to the axis of the tube being formed.

In practising the invention, a steel strip of suitable thickness and width is fed to the machine and the tube is gradually 105 formed by a number, which may be five, or more pairs of rolls B, the surface of the rolls being suitably grooved to gradually bend the strip into almost perfect circular form. The tube thus formed is then sub- 110

mitted to the action of my improved forming roll C and flat forming die D, the forming dies moving with the tube beneath the forming roll and effecting a tightening of the butt joint, and a closure of the tube. It will be seen that this operation can all be performed in one machine and without being under the necessity of transferring the tube to a separate closing former.

The degree of pressure by the roll and die blocks may be regulated by the adjustable screws 30, operating to move bearing blocks 12 in the guide way 31. It will also be evident that my improved forming roll 15 be applied to some series of die blocks may be applied to some of the preliminary operations in the formation of tubing, and not merely for finally closing and setting the joint of the tube. By variations in the form of die surfaces, various kinds of cylindrical, oval and angular shapes may be made.

What I claim as my invention is:

1. In a tube forming machine, in combination, a pivoted forming roll, a support for the tube to be formed comprising a stationary support and a series of movable

elongated flat dies in endless chain formation contacting with the tube under the roll, and means for moving the dies continuously 30 to and from supporting position.

2. The device of claim 1 with the addition of guiding means for the dies.

3. In a tube forming machine, in combination, a forming roll, a plane surface 35 opposite the same, an endless series of flat forming dies and means for moving said dies longitudinally with the tube over the plane surface.

4. In a tube forming machine, in combination, a forming roll, a plane surface opposite the same, an endless series of flat forming dies and means for moving said dies longitudinally with the tube over the plane surface, at least two of said dies being 40 on the surface together, and forming thereon a continuous die surface which engages the tube.

In witness whereof I have hereunto set my hand in the presence of two witnesses. 50

JAMES LUTHER HOSACK.
